(57) **CLAIM**

The ornamental design for a travel drying container, as shown, and described.

DESCRIPTION

FIG. 1 is a perspective view of the travel drying container in the open position;

FIG. 2 is a top view of the travel drying container in the open position;

FIG. 3 is a bottom view of the travel drying container in the open position;

FIG. 4 is a side view of the travel drying container in the open position;

FIG. 5 is a front view of the travel drying container in the open position;

FIG. 6 is a perspective view of the travel drying container in the closed position;

FIG. 7 is a top view of the travel drying container in the closed position;

FIG. 8 is a bottom view of the travel drying container in the closed position;

FIG. 9 is a side view of the travel drying container in the closed position;

FIG. 10 is a front view of the travel drying container in the closed position; and,

FIG. 11 is a rear view of the travel drying container in the closed position.

The broken line showing of the container from no part of the claimed design.
